(57) **CLAIM**

The ornamental design for a display screen or portion
thereof with icon, as shown and described.

DESCRIPTION

The file of this patent contains at least one drawing/photograph
executed in color. Copies of this patent with color
drawing(s)/photograph(s) will be provided by the Office
upon request and payment of the necessary fee.

The FIGURE is a front view of a display screen or portion
thereof with icon showing the claimed design.

(Continued)

The dashed broken lines in the FIGURE show a display screen or portion thereof, and form no part of the claimed design.
